DESIGN FOR A CARRYING HANDLE

Frank Zessau, Los Angeles, Calif

Application November 8, 1933, Serial No. 49,675

Term of patent 7 years

To all whom it may concern:

Be it known that I, FRANK ZESSAU, a citizen of the United States, residing at Los Angeles, in the county of Los Angeles, and State of California, have invented a new, original, and ornamental Design for a Carrying Handle, of which the following is a specification, reference being had to the accompanying drawing, forming part thereof.

I claim:

The ornamental design for a carrying handle as shown.

FRANK ZESSAU.
